THERMOSTATIC SWITCH HOUSING FOR FIRE ALARM SYSTEMS

Galen O. Chapman, Boulder Creek, Calif.

Application September 8, 1954, Serial No. 32,190

Term of patent 14 years

(Cl. D52—7)

Fig. 1 is a perspective view of a thermostatic switch housing for fire alarm systems embodying my new design.

Fig. 2 is a side elevational view of the switch shown in Fig. 1.

Fig. 3 is an end elevational view of the switch shown in Figs. 1 and 2.

I claim:

The ornamental design for a thermostatic switch housing for fire alarm systems, as shown.
